AMPLIFYING COUPLING BETWEEN A LOW RESISTANCE SOURCE AND A HIGH RESISTANCE CIRCUIT

William H. Bussey, Chicago, Ill., assignor, by mesne assignments, to Robert L. Kahn, trustee

Application May 29, 1945, Serial No. 596,503

7 Claims. (Cl. 179—171)

1

This invention relates to an electrical apparatus and more particularly to an amplifying coupling between a low resistance low voltage source of current and a high resistance relatively high voltage circuit.

There are many low resistance low voltage sources of power whose output it is desired to utilize for recording, indicating or control purposes in general. Thus, thermal couples forming pyrometer systems, barrier type light cells, and even bridges and potentiometers under some conditions may be classed as low resistance low voltage sources of current. Such source generally has a voltage output which is measured in millivolts with currents measured in milliamperes. The resultant power output is of the micro-watt order.

The voltage output of low voltage low resistance power sources previously mentioned does not vary at a rapid rate. Thus, a thermal couple whose voltage output is proportional to a temperature difference may vary its voltage output as the temperature varies. However, even by such low frequency standards as 60 cycles per second, the variation of voltage of such a thermal couple is extremely small. It is clear, therefore, that if the voltage output of such low resistance low voltage sources is to be amplified, direct current amplifying circuits must be relied upon.

Direct current amplifiers for low voltage power sources suffer from serious drawbacks. Due to the necessity for continuous metallic circuits, excepting through the inter-electrode space in vacuum tubes, it is impossible to provide any potential isolation for various portions of an amplifier. Contact potentials generated at various junctions in an amplifying system and usual tube disturbances result in drifts of potentials of the order of the potential output of the low resistance sources. It is clear, therefore, that feeding a low voltage output from power sources previously described directly into control elements of conventional direct current amplifiers is impractical.

By virtue of the invention herein, it is an object to provide a simple and effective means for coupling a low voltage low resistance power source to any conventional amplifier. The invention is based upon the cathode emission characteristic of a two element vacuum tube. As is well known, a diode having a thermionic cathode and anode within an evacuated container may have the space current between the electrodes altered or controlled in two ways. If the temperature of the cathode is maintained at a constant value, the space current between the cathode and anode may be varied over a range by controlling the positive bias of the anode with respect to the

2

cathode. A characteristic curve for a diode generally has a lower and upper bend. At the upper bend of the curve, saturation takes place so that, beyond a certain anode potential, space current remains either constant or increases relatively little, assuming no ionization of remanent gas particles. It is also possible to vary the space current by maintaining the anode potential at a saturating value and vary the temperature of the emitting cathode. The invention herein relies upon this latter property.

In accordance with the invention herein, there is provided a pair of diodes so connected that the voltage output from a low voltage low resistance power source unbalances a predetermined distribution of cathode heating current in said diodes. The unbalance results in one diode cathode having its heating current increased, while the other cathode has its heating current decreased. By virtue of this, the electron emission is differentially affected, thus resulting in a differential variation of anode to cathode current in each diode. It is understood that the potential applied to both anodes is sufficient to maintain saturation in both diodes under all normal operating conditions but below that at which any arc or gas discharge may be initiated.

By utilizing such a double diode arrangement in a null control, the operating range of the diode, both as regard cathode temperature and anode bias, may be made quite small. By virtue of such an arrangement, the cathode emission and anode potential may be maintained at predetermined calibrated values. However, the system may be used without the null expedient.

The diodes are disposed in a conventional load circuit having a load resistor for each diode. The variation in space current through load resistors results in a variation of potential drop across said resistors. Such drops are large in comparison to the magnitude of the original low voltage power source. Using null operation, it is evident that the potential drops across the load resistors may be the basis for this method of regulation. By causing such drops to retain their predetermined values, the system may be maintained in a balanced condition. On the other hand, if the system is permitted to respond to the original voltage from the low resistance power source without any attempt to balance the same out, the large potential drops across the load resistors may be fed to conventional amplifiers. Such large drops may be as much as one thousand times as great as the original low potential, so that undesired disturbances in the amplifier will no longer be significant. By using diodes that

are as near alike as possible, disturbances within the diodes will generally tend to cancel out.

Under certain conditions, the diodes may be energized by alternating potentials having a peak value sufficient for saturation under all normal operating conditions. The frequency of this alternating potential should be substantially higher than the frequency of any normal potential variation present in the low resistance source. Thus, the low voltages may be used for modulation purposes and the resulting output be fed through coupling condensers to conventional amplifiers.

While the invention may be used with advantage particularly in connection with low voltage low resistance sources, it is by no means restricted to this. Thus, low voltages from high resistance or impedance sources may be utilized. In such a case, it is clear the null method for balancing out potentials would be necessary to eliminate a tendency for drawing any current from such high resistance sources. However, it is preferred to use the system in connection with low resistance sources so that currents having a value significant in comparison to the value of the heating current in the cathodes may be drawn even if only for a short time.

The two diodes are preferably within one envelope and are as alike as possible, both in their construction and operating conditions. The cathodes themselves are preferably of the filamentary type since manufacturing difficulties would make an indirectly heated cathode expensive and of doubtful value. In general, a variation of heating voltage of about one per cent can cause a significant variation in electron emission of a cathode. Under certain conditions, the percentage variation of voltage may be even smaller. It follows, therefore, that filamentary cathodes operated at low voltages with minute heating currents are advantageous. Such a cathode has the advantage that it may be energized by one or more dry cells whose output voltage may be maintained at a constant value. It is, of course, possible to energize the cathodes with alternating current or from any other power source providing that the average value is maintained constant. In general, however, an alternating current heating source will result in temperature alternations which may be objectionable.

Filamentary cathodes may be made of wire or any suitable material and treated with suitable compounds for electron emission. Thus, it is possible to provide platinum wire having a fineness of the order of one-ten thousandth of an inch. Such a platinum wire may be coated with suitable compounds for promoting electron emission at high temperatures. There are also on the market small vacuum tubes particularly adapted for hearing aids having filamentary cathodes drawing twenty milli-amperes at about five-eighths of a volt. Such tubes may be operated as diodes and used satisfactorily. For a further description of the invention, reference will now be made to the drawing wherein the single figure shows a diagrammatic representation of a system embodying the invention.

Vacuum tube 10 has cathodes 12 and 13 preferably formed as one continuous length of wire. Disposed around each of the cathodes are anodes 14 and 15 respectively. Inasmuch as the construction of a double diode is well known in the art, no detailed structural description will be given. If desired, the two diodes may be separated into two separate structures.

Between cathodes 12 and 13, junction 17 may

be provided. This point is preferably located at the mid-point of the two cathodes so that the resistances of cathodes 12 and 13 are equal.

Cathodes 12 and 13 have leads 18 and 19 going to a steady source of heating current 20. This source of heating current should have a constant power output and, in most instances, may consist of a battery. Bridged across leads 18 and 19 are resistances 21 and 22 with junction 23 at the midpoint. Resistances 21 and 22 are preferably equal in value to the resistances of filamentary cathodes 12 and 13 under normal operating conditions.

From junction 23, a lead goes to terminal 24 while, from junction 17, a lead goes to terminal 25, these terminals constituting input terminals to the system. Terminal 25 is connected by lead 26 to any low voltage source of power 27 as previously described. Source 27 has lead 28 connecting it to neutralizing low voltage source 29 and then the circuit continues along lead 32 back to terminal 24. Neutralizing low voltage source 29 is provided for balancing out any low voltage from source 27 so that the net potential difference between input terminals 24 and 25 may be reduced to zero. The neutralizing low voltage source may consist of a battery and potentiometer. The means for varying the value of the neutralizing low voltage may be either manual or automatic and, if the latter, may be operated from the output of the entire system. If desired, the neutralizing low voltage source may be omitted and low voltage source 27 connected directly across terminals 24 and 25.

Anodes 14 and 15 are connected by leads 35 and 36 to load resistors 37 and 38 respectively. Load resistors 37 and 38 each have a value substantially equal to the static resistance of each diode under normal operating conditions. Lead resistances 37 and 38 are connected to junction point 39. From junction 39, a connection goes to high potential source 40. This may consist of a battery or rectified power supply with the positive terminal connected to junction 39. The negative terminal of the high voltage supply is connected by lead 41 to junction point 17. The voltage of potential source 40 is sufficiently high to maintain saturation in the diodes under normal operating conditions. Under certain conditions, voltage source 40 may be an alternating potential of a suitable high value and preferably having a uniform peak voltage.

Bridged across high voltage source 40 may be resistance 42 with which wiper 43 cooperates to provide a potentiometer. Wiper 43 is grounded so that any desired potential level in the high voltage supply may be established as ground. This ground connection is provided for the convenience of the amplifier into which the system may feed. The ground may, of course, be omitted and other portions of the system may be established as ground if desired.

Leads 35 and 36 pass on to control grids 45 and 46 of vacuum tube amplifiers 47 and 48. These amplifiers are merely representative and may be varied to suit conditions. Thus, as shown, vacuum tubes 47 and 48 have cathodes 49 and 50 connected together through suitable bias resistance 51 to ground. By virtue of the establishment of the ground connection at a potential equal to or near the positive potential of source 40, the potentials of grids 45 and 46 may be readily established at a suitable value with respect to cathodes 49 and 50 without elaborate means.

Tubes 47 and 48 have anodes 53 and 54 connected through load resistors 55 and 56 to a suitable source of B plus potential. This potential may either be direct or alternating as desired. Output leads 57 and 58 taken at anodes 53 and 54 may feed succeeding amplifiers or suitable indicating or operating means. Thus, output leads 57 and 58 may control servo-means for varying neutralizing low voltage source 29 to maintain the system in balance.

In the event that the anode to cathode potential on the diodes is alternating, coupling condensers between control grids 45 and 46 and the diode anodes may be inserted. In such a case, it is clear that conventional amplifier stages may be used instead of direct current amplifiers.

It is possible to couple an indicator to the control of neutralizing low voltage source 29 with the indicator calibrated to show the voltage necessary to balance the output from low voltage 27. The indications may also be in terms of temperature or any desired characteristic. It is clear that the variation of neutralizing low voltage to maintain cathodes 12 and 13 balanced involves a null method. Such a method is highly advantageous since departure from carefully calibrated conditions with regard to cathode temperature and anode potential is not necessary. However, in the event that the null balancing is not desired and voltage source 27 feeds directly into terminals 24 and 25, then other indicating means will be necessary. Such indicating means may be actuated by the outputs from leads 57 and 58.

What is claimed is:

1. In a system of the character described, a vacuum tube diode system having two cathodes and two anodes, a heater circuit for energizing each cathode to electron emission, electric connections disposing said heater circuits in series to provide a common heater terminal and two end heater terminals, a steady source of potential connected to said end terminals, said steady potential source having a neutral point normally at the same potential as the common terminal of said heater circuits, said system being adapted to have a low resistance low voltage source of power connected between said neutral point and common terminal, a cathode anode circuit for each diode including a resistive load and source of steady potential, said two cathode-anode circuits being similar, said system having an output terminal at the end of each resistive load adjacent a diode electrode, said last-named steady potential being high enough to maintain saturation conditions.

2. In a system of the character described, a pair of diodes each having a filamentary cathode and anode, a common connection between said filaments so that said filaments are in series, a direct current source connected across said two series filaments for supplying heating current, said direct current source having a neutral point whose potential is normally substantially equal to the potential of the common filament connection, said neutral point and common connection being input terminals for a low resistance low voltage source of power whose output potential is measured in milli-volts and whose output current is normally measured in milli-amperes, said filaments being so designed that they are energized by a heating current normally measured in milli-amperes at a sufficiently low voltage so that upon insertion of said source of power said heating currents are sensibly affected and

result in a significant change in electron emission, two resistive loads in series connected across said anodes, a source of steady direct potential having its negative terminal connected to said common filament connection and its positive terminal connected to the common connection between said resistive loads and an output circuit across said anodes, said steady potential being high enough to maintain saturation conditions.

10 3. The system of claim 2 wherein a ground is taken at a point in said source of saturating potential having a potential near the positive terminal whereby the output terminals may be at a potential sufficiently close to ground so that connection to conventional vacuum tube amplifiers is possible.

4. The system of claim 2 wherein a point on said source of saturating potential is grounded so that the positive terminal is at or near ground, 20 a pair of opposed vacuum tube amplifiers and direct connections from said output terminals to the control electrodes of said vacuum tube amplifiers.

5. In a system of the character described, a vacuum tube diode system having two filamentary cathodes and two anodes, a series connection between said filaments to provide a common filament terminal and two end filament terminals, a steady source of direct potential connected to said end filament terminals for heating said filaments in series, said source having a neutral point whose potential is intermediate the potentials of the end filament terminals, said neutral point and common filament terminal constituting the

35 input terminals for the system and being adapted to have a low resistance, a low voltage source of power connected thereto, two resistive loads connected in series between the diode anodes, said loads having a common terminal, a second 40 source of potential connected between said load common terminal and common filament terminal and being high enough to maintain diode saturation conditions, said system having output terminals at the diode anodes whereby a potential 45 at the input of the system differentially changes the distribution of heating current in said two filaments and thereby differentially changes the space currents through said diodes.

6. The system of claim 5 wherein said steady 50 source of direct potential for heating said filaments includes a resistor connected across said end filament terminals and wherein said neutral point is an intermediate point on said resistor.

7. The system of claim 5 wherein said steady 55 source of direct potential for heating said filaments includes a resistor connected across said end filament terminals, said resistor having a resistance substantially equal to that of the series filaments under operating conditions and 60 wherein said neutral point is an intermediate point on said resistor.
